O. J. KENDON.

SAW.

APPLICATION FILED APR. 12, 1919.

1,319,712.

Patented Oct. 28, 1919.

By his Attorneys

Inventor
Ole J. Kendon,
¹⁸ Edgar Hale

UNITED STATES PATENT OFFICE.

OLE J. KENDON, OF PORT WASHINGTON, NEW YORK.

SAW.

1,319,712.

Specification of Letters Patent.

Patented Oct. 28, 1919.

Application filed April 12, 1919. Serial No. 289,704.

To all whom it may concern:

Be it known that I, OLE J. KENDON, a citizen of the United States, and residing at Port Washington, L. I., in the county of 5 Nassau and State of New York, have invented certain new and useful Improvements in Saws, of which the following is a specification, such as will enable those skilled in the art to which it appertains to 10 make and use the same.

This invention relates particularly to what are known as mechanical saws for use in cutting down trees, and the object thereof is to provide an improved device of this class 15 which is simple in construction, efficient in operation and which may be operated by one man; and with this and other objects in view the invention consists in a device of the class specified, constructed and operating as 20 hereinafter described and claimed.

The invention is fully disclosed in the following specification, of which the accompanying drawing forms a part, in which the separate parts of my improvement are designated by suitable reference characters in 25 each of the views, and in which:

Figure 1 is a view showing my improved saw and indicating the method of its use;

Fig. 2 a section of the handle end of the 30 device on the line 2—2 of Fig. 3;

Fig. 3 a section on the line 3—3 of Fig. 2;

Fig. 4 a section on the line 4—4 of Fig. 3;

Fig. 5 a partial section on the line 5—5 of Fig. 1;

Fig. 6 a sectional view of a rotary cutter which I employ and a number of which are used; and,

Figs. 7 and 8 are detail views of a drive chain, forming part of my improved saw 40 and which works in connection with a gear blade and the rotary cutters to operate said cutters.

In Fig. 1 of the accompanying drawing, I have shown at *a* the body of a tree and at *b* 45 my improved saw, and in the construction of said saw I provide a handle member *c*, having at one end a hand grip or handle *c*², and in the opposite end of which is a transverse chamber *c*³ having an extension in the 50 direction of the hand grip *c*² and forming a supplemental chamber *c*⁴. The handle member *c* is preferably composed of two parts secured together by bolts, screws or other devices *c*⁵, and mounted in the supplemental

chamber *c*⁴ is a pin *d* provided with a pinion 55 *d*² and gear *d*³.

Secured in the chamber *c*³ is a gear blade *e*, the opposite sides and ends of which are provided with continuous gear teeth *e*², and this gear blade may be of any desired length 60 and the ends thereof are rounded as shown in Figs. 1 and 2. Mounted in and centrally of the chamber *c*³ is a transverse shaft *f* which also passes through the inner end of the gear blade *e*, and which is provided 65 within said chamber with a gear *f*², and at one end with a crank handle *f*³, and the gear *f*² meshes with a supplemental gear *h* mounted in the chamber *c*³, and which operates in connection with the pinion *d*². 70 I also provide a drive chain *i* which in use extends entirely around the gear blade *e*. A plurality of cutters *j* are loosely mounted between the drive chain *i* and the gear blade *e*, and which have a combined rotary and 75 longitudinal movement around said blade and which are held in place and operated by the chain *i*.

The chain *i* is made up of link members *i*² of the shape, form and construction shown 80 in Figs. 7 and 8, which comprise body portions *i*³ and opposite side projecting ears *i*⁴ which are alternately arranged on the opposite sides of the body portions, and in connecting these link members to form the 85 chain, the ears *i*⁴ of the separate link members are overlapped and connecting pins are passed through holes *i*⁵ in the ears *i*⁴. The body portions of the link members *i*² are provided on their inner sides with recesses 90 *i*⁶. The cutters *j* consist of opposite similar side plates *j*², which are star-shaped in form or provided with cutting teeth *j*³, and said plates are connected and equally spaced by central gear bodies *j*⁴ having gear teeth 95 *j*⁵, which operate in connection with the link members of the chain *i* and also in connection with the gear teeth *e*² of the gear blade *e*. In practice the desired number of the cutters *j* are mounted between the gear 100 blade *e* and the drive chain *i*, and it will be apparent that the gear blade *e* fits between the opposite sides *j*² of the cutters *j* and drive chain *i* also operates in and between the opposite sides of said cutters as is clearly 105 indicated in Figs. 1, 2 and 3, and the chain *i* is driven by the gear *d*³ on the pin *d*.

I also provide a tree attaching device *k* by

means of which my saw is connected with the body of the tree, and this device comprises a main socket member k^2 having in one side thereof, in the form of construction 5 shown, a longitudinal slot k^3 , and in which is mounted a telescopic arm k^4 provided with a pin k^5 , which is movable in said slot k^3 . The arm k^4 is provided at its outer end with a prong k^6 adapted to be driven into the body 10 or trunk of the tree, and mounted in the socket member k^2 is an expansion spring k^7 which normally serves to force the saw outwardly. The main socket member k^2 is also provided with a forked extension k^8 having 15 jaws k^9 between which the gear blade e passes, and said gear blade is secured between said jaws by a headed pin k^{10} provided with a thumb and finger set nut k^{11} by means of which the said gear blade e 20 may be securely clamped between the jaws k^9 , and in the operation of the device the chain i and cutters j pass through the forked extension k^8 of the part k as clearly shown in Fig. 5.

25 The gear blade e is provided centrally and longitudinally thereof with a plurality of spaced apertures e^3 , and the pin or bolt k^{10} may be passed through any of said apertures and the attaching device k may thus 30 be adjusted longitudinally of the saw. The jaws k^9 of the attaching device are spring jaws and are provided at their ends or where the pin or bolt k^{10} passes therethrough with parallel fingers k^{12} , which also pass through 35 said apertures, and which serve to retain the saw device in position and prevent its vibration or lateral movement toward and from the tree, but it must be understood that my invention is not limited to any particular 40 means for connecting the saw device with the body of the tree and any suitable construction may be employed for this purpose.

It will be noted on a consideration of Figs. 3 and 4 of the drawing that I employ a reinforcing plate m , which is secured to the 45 inner face of one of the side parts of the handle c by screws m^2 , and the shafts d and f pass through the plate m , or the pinion d^2 on the shaft d passes through an aperture 50 m^3 in said plate, while the shaft f has a bearing in said plate, and the gear h , or the shaft h^2 thereof, also has a bearing in the plate m as well as in one of the side parts of the handle c . The reinforcing plate serves 55 to reinforce or strengthen the handle c where the gears and shafts connect therewith, and it will be noted on a consideration of Fig. 2 of the drawing that two of the screws m^2 pass through the inner portion of the blade 60 e and serves to retain said blade in proper position.

The operation will be readily understood from the foregoing description when taken 65 in connection with the accompanying drawing and the following statement thereof. In

the beginning of operations the saw is connected with the body of the tree, as shown and described, or in any other suitable way, and the handle c^2 is gripped by one hand of the operator and the crank f^3 operated by 70 the other, and this results in driving the chain i around the gear blade e longitudinally thereof and in the plane thereof as will be readily understood, and in this operation the cutters j are carried around said 75 blade longitudinally thereof, and at the same time are independently rotated and this gives said cutters a rapid rotary and longitudinal movement around said blade and the body or trunk of the tree is cut transversely 80 thereof as indicated in Fig. 1, and in this operation the saw device is constantly pressed in the direction of the tree by the operator against the operation of the spring k^7 . This spring, however, is a light or weak 85 spring and but slight pressure is necessary to force the saw in the direction of the tree body. It will be apparent that in the inward movement of the saw device, the kerf is cleared by the chain i as it passes between 90 the cutting teeth j^3 of the cutters j , and the teeth and grooves in the face of the chain i will facilitate this operation.

Although I have described my improved saw device as one adapted to be operated by 95 one man, this method of operation is not, of course, essential and means may be provided whereby said saw device may be operated by two men, and while I have shown and described my improved saw device as 100 of certain detailed construction, it will be understood that in the construction of the saw device, as well as in the construction of the means herein shown and described for securing the saw device to the tree, my invention is not limited to such details of construction, and changes therein and modifications thereof may be made, within the scope 105 of the appended claims, without departing from the spirit of the invention or sacrificing its advantages.

Having fully described my invention, what I claim as new and desire to secure by Letters Patent, is:—

1. A saw device of the class described comprising a handle member having a projecting gear blade, a drive chain extending around said gear blade longitudinally thereof, and rotary cutters mounted between said blade and said chain and held in position by 115 said blade and said chain and adapted to be driven around said blade by said chain.
2. A saw device of the class described comprising a handle member provided with a projecting blade member, a drive chain 120 movable longitudinally of and around said blade, and rotary cutters mounted independently between said chain and said blade and adapted to be carried around said blade by said chain, said cutters and said chain co- 125 130

operating to hold themselves in operative connection with said blade.

3. In a saw device of the class described, the combination with a gear blade the edges of which are provided with continuous gear teeth, a drive chain inclosing said blade longitudinally thereof and independent cutters mounted between said blade and said drive chain and having gears which operate in connection with the gear teeth of said blade and the links of said chain, said chain and said cutters coöperating to hold themselves in position and in connection with said blade.

15 4. In a saw device of the class described, a plurality of cutting devices comprising similar side plates having cutting teeth, a central body portion for spacing and securing said side plates together, and gear teeth 20 formed on said body portion.

5. A saw device of the class described comprising a handle member divided centrally and longitudinally into two approximately similar parts, means for securing said parts 25 together, recesses formed in the abutting faces of said parts, a gear blade detachably mounted in the recessed portion of said handle member and projecting therefrom, a drive chain extending around said gear 30 blade longitudinally thereof and about the periphery thereof, rotary cutters mounted between said chain and said gear blade and adapted to travel around said blade, gears mounted in the recessed portion of said 35 handle member and operating in connection

with said chain, and means mounted transversely of said handle member for operating said gears to rotate said chain.

6. A saw device of the class described comprising a handle member divided centrally 40 and longitudinally into two approximately similar parts, means for securing said parts together, recesses formed in the abutting faces of said parts, a gear blade detachably mounted in the recessed portion of said handle member and projecting therefrom, a drive chain extending around said gear blade longitudinally thereof and about the periphery thereof, rotary cutters mounted 45 between said chain and said gear blade and adapted to travel around said blade, a transverse shaft mounted in said handle member and provided at one end thereof with a crank handle, a gear mounted on said shaft within the recessed portion of the handle 50 member, another gear mounted in said recessed portion and in operative connection with said chain, and means for gearing said gears together whereby the rotation of said crank will move said chain about said gear 55 blade.

In testimony that I claim the foregoing as my invention I have signed my name in presence of the subscribing witnesses this 5th day of April, 1919.

OLE J. KENDON.
